CLAIM

The ornamental design for a bottle lid, as shown and described.

DESCRIPTION

FIG. 1 is a front and top perspective view of a bottle lid, showing our design.

FIG. 2 is a rear and top perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof; and,

FIG. 8 is a bottom plan view thereof.

The broken lines depict portions of the bottle lid that form no part of the claimed design, with the outermost circular broken line in FIG. 8 also forming the boundary to the claim.

1 Claim, 8 Drawing Sheets
